UNITED STATES PATENT OFFICE.

GEORGE W. HULSHIZER, OF STEWARTSVILLE, NEW JERSEY, ASSIGNOR TO INGERSOLL-RAND COMPANY, OF JERSEY CITY, NEW JERSEY, A CORPORATION OF NEW JERSEY.

ROCK-DRILL OSCILLATING VALVE.

Application filed October 10, 1925. Serial No. 61,634.

This invention relates to fluid actuated rock drills, but more particularly to an improved form of oscillating distributing valve.

5 The objects of the invention are to secure a light, quick-acting oscillating or pivoted valve which may be constructed of tubular form, having convex or cylindrical seating surfaces cooperating with the hollow bore 10 of the valve chest.

Other objects of the invention are to permit the valve to be readily and quickly assembled in the valve chest and obtain a simple and efficient means for restricting the 15 flow of pressure fluid over one end of the valve as the valve oscillates.

Further objects of the invention will hereinafter appear, and the invention is shown in one of its preferred forms in the 20 accompanying drawings, in which

Figure 1 is a longitudinal sectional elevation in diagrammatic form showing the construction;

25 Figure 2 is a similar view of the parts in a different position;

Figure 3 is a perspective view of the valve; and

Figure 4 is an end view of the valve.

Referring to the drawings, the portion 30 of a rock drill shown, preferably of the hammer type, comprises the cylinder A, reciprocating piston B, valve chest C preferably formed integral with the cylinder, and the oscillating valve D in the valve chest.

35 Pressure fluid for the rock drill is supplied at the inlet E and in this instance the cylinder is provided with the piston controlled free exhaust port F.

Distributing ports G and H lead from 40 the interior of the valve chest to the opposite ends of the cylinder, and ports J and K afford communication between the inlet and the valve chest.

The valve D is of semi-tubular or trough 45 shaped form, but, for lightness in construction, is preferably cut away at the upper portions L and O, leaving a bridge P at the center through which the pivot pin Q passes.

50 The convex seating surfaces R and S of the valve as shown, intersect at an angle to the longitudinal axis of the valve and extend from the central portion T of the valve outwardly to the ends. These convex

surfaces R and S are preferably cylindrical and have the same radius of curvature as the peripheral surface of the bore U of the valve chest, wherewith they cooperate to control the admission of pressure fluid to the cylinder. As a result of this construction, perfect seating is obtained between the valve and valve chest over the ports G and H. Furthermore, the curved seating surfaces enable the valve to be made more cheaply out of a tubular section and require less room for the valve.

The valve D may be constructed in any suitable manner, as, for instance, by stamping, or else it may be cut out of a solid bar of steel or other suitable material. The 70 valve chest C, for convenience and cheapness of construction, is preferably closed at one end V and the valve is inserted in the chest from the open end W. The pivot Q is inserted transversely through the chest 75 and through the valve, and a plug X then closes the valve chest. This construction of valve chest and valve is simple and cheap to manufacture and the valve may be readily and quickly inserted in the chest and removed therefrom.

In the operation of the device let it be assumed that the piston is moving forwardly, as indicated in Figure 1, in which case pressure fluid is supplied from the inlet E through the port J, over the rearward end Y of the valve and through the port G to the rearward end of the cylinder. The forward end of the cylinder is open to atmosphere at the exhaust port F so that the forward cylinder port H is closed by the valve. As the piston over-runs the exhaust port F, as shown in Figure 2, the valve is oscillated on its pivot Q to close the rearward cylinder port G and open the forward cylinder port H to permit pressure fluid to drive the piston rearwardly, and this operation continues as the valve oscillates. This oscillation is caused by compression ahead of or behind the piston, as the case may be.

100 Means are preferably provided for restricting the flow of air over one or both ends of the valve as the valve oscillates, since the wire drawing effect thus produced aids in throwing the valve quickly. In this instance the restriction is shown at the forward end of the valve, and for this purpose the inner face of the valve chest plug X is

recessed at *a* and the forward end *b* of the valve cooperates with the edge or wall *c* of the recess to effect an early cut-off during the closing movement of the valve, and for 5 retarding admission of air to the cylinder during the opening movement of the valve at the forward end. This construction having the recess or chamber *a* materially lowers the consumption of pressure fluid in 10 a rock drill.

I claim:

1. In a fluid actuated rock drill, the combination of a cylinder and piston, a valve chest having a cylindrical bore, and a fluid 15 actuated oscillatory distributing valve having convex seating surfaces adapted to cooperate with the peripheral surface of the bore for gradually cutting off the admission of pressure fluid to the cylinder.

2. In a fluid actuated rock drill, the combination of a cylinder and piston, a valve chest having a cylindrical bore, a fluid actuated oscillatory distributing valve in the bore, and diverging convex seating surfaces 25 of uniform radius throughout their lengths cooperating with the peripheral surface of the bore for controlling the admission of pressure fluid to the cylinder.

3. In a fluid actuated rock drill, the combination of a cylinder and piston, a valve chest having a straight cylindrical bore, and a fluid actuated oscillatory distributing valve in the bore, said valve having convex 30 seating surfaces adapted to cooperate with the peripheral surface of the bore for gradually cutting off the admission of pressure fluid to the cylinder as the piston nears the end of its stroke, and a pin inserted through the valve and the valve chest to act as a 35 pivot for the valve.

4. In a fluid actuated rock drill, the combination of a cylinder and piston, a valve chest on the cylinder having a straight cylindrical bore, and a fluid actuated distributing valve inserted longitudinally in the bore, 45 said valve having diverging convex seating

surfaces cooperating with the peripheral surface of the bore for gradually cutting off the admission of pressure fluid to the cylinder as the piston nears the end of its 50 stroke.

5. In a fluid actuated rock drill, the combination of a cylinder and piston, a valve chest on the cylinder having a straight cylindrical bore, inlet passages leading from the 55 bore to the ends of the cylinder, and a fluid actuated distributing valve in the bore oscillating in a plane extending through the longitudinal axis of the bore to control the inlet passages, said valve having diverging 60 convex seating surfaces cooperating with the peripheral surface of the bore for gradually cutting off the admission of pressure into the cylinder.

6. In a fluid actuated rock drill, the combination of a cylinder and piston, a valve chest having a cylindrical bore closed at one end, an oscillating distributing valve of form adapted to be inserted longitudinally through the open end of said valve chest, 70 said valve having diverging convex surfaces to cooperate with the peripheral surface of the bore for controlling the admission of pressure fluid to the cylinder, and a plug for closing said open end of the valve chest 75 having a chamber, the edges of the valve cooperating with the walls of said chamber to restrict the flow of pressure fluid at this point as the valve oscillates.

7. In a fluid actuated rock drill, the combination of a cylinder and piston, said cylinder having a free exhaust port controlled by the piston, a valve chest having a cylindrical bore, and a fluid actuated oscillatory distributing valve having diverging convex 85 seating surfaces adapted to cooperate with the peripheral surface of the bore for gradually cutting off the admission of pressure fluid to the cylinder.

In testimony whereof I have signed this specification.

GEORGE W. HULSHIZER.
